Application November 29, 1935, Serial No. 59,830
In Germany July 27, 1935

Term of patent 14 years

To all whom it may concern:

Be it known that we, Albert Lasch and Karl Frei, citizens of Germany, residing at 26 Moltkestr. Stuttgart Bad-Cannstatt, and 5 Gerhardstr., Ober-Esslingen, Germany, respectively, have invented a new, original, and ornamental Design for a Mixing Trough for Plastic Material or the like, of which the following is a specification, reference being had to the accompanying drawing, forming a part thereof.

Fig. 1 is a side elevational view of a mixing

trough for plastic material or the like showing our design.

Fig. 2 is a top plan view.

Fig. 3 is an end elevational view.

We claim:

The ornamental design for a mixing trough for plastic material or the like, substantially as shown.

ALBERT LASCH.
KARL FREI.
